UNITED STATES PATENT OFFICE.

SAMUEL J. BINGHAM, OF BINGHAMTON, NEW YORK, ASSIGNOR OF ONE-HALF TO WILLIAM W. CLARK, OF CHICAGO, ILLINOIS.

ANTI-RATTLER FOR THILL-COUPINGS.

SPECIFICATION forming part of Letters Patent No. 369,428, dated September 6, 1887.

Application filed March 26, 1887. Serial No. 232,476. (No model.)

To all whom it may concern:

Be it known that I, SAMUEL J. BINGHAM, of Binghamton, in the county of Broome and State of New York, have invented certain new and useful Improvements in Anti-Rattlers for Thill-Couplings, of which the following is a description, reference being had to the accompanying drawings, forming a part of this specification, in which—

10 Figure 1 is a side view of a thill-coupling with my improved anti-rattler applied thereto, the axle, a portion of the axle-clip, and coupling-bolt being in transverse section. Fig. 2 is a detached view in perspective of my improved 15 anti-rattler as the same appears when ready for use, and Fig. 3 is a vertical sectional view thereof.

Similar reference-letters in the various figures designate like parts.
20 My invention has for its object to provide a cheap, simple, and durable device for the prevention of rattling in thill-couplings; to which end said invention consists in so inclosing the usual rubber compression-block and combining it with other elements as that it may be protected from contact with oil and other things injurious thereto, as well as from frictional contact with the shaft-eye, while it may be given an expansion only in the direction in 25 which its pressure is required to be exerted. Moreover, I desire to provide a durable friction-surface for engagement with the shaft-eye, to which surface oil may be applied, when desired, to prevent cutting. I accomplish said objects in the following manner:

30 In the drawings, A represents a vehicle-axle, to which is attached in any well-known way the usual clip, B.

35 C represents an ordinary shaft having a shaft-eye, C', loosely coupled to the eye of the clip by means of the shaft-bolt D.

40 Between the shaft-eye and the face of the clip is interposed my improved anti-rattler, of which E constitutes the case. Said case is 45 formed from cast or malleable iron or other suitable metal, and is provided with a concave

face upon its front adapted to conform to the curved surface of the shaft-eye. Within the back of said case or block is formed a suitable cavity, E², within which is inserted a rubber or other elastic compression-block, F. A metal plate, G, is inserted within the cavity E² upon one side of said compression-block, which serves to form a bearing for the end of a set-screw, H, by which the block G may be compressed. 55 Upon placing said device in position, as shown in Fig. 1, and turning the screw H against the plate G, the block F is compressed; but, being prevented from lateral movement by the walls of the case E, it presses against the face of the clip and throws the case E forward against the shaft-eye. Thus it will be seen that the block is protected from contact with oil and other substances which tend to dissolve or injure it, while a permanent and durable friction-surface is provided for the shaft-eye. Moreover, 60 oil may be applied to said surface when needed, which is not practicable with the devices heretofore employed.

65 I am aware that it is old to extend the yoke 70 of the axle-clip forward beneath the shaft-eye to form a support for a wedge-block between which and said shaft eye is inserted a metal-faced compression-block adapted to be compressed by means of a set-screw placed in the 75 yoke. I am likewise aware that it is not new to place a compression-block in a metallic casing covering the top, bottom, sides, and back thereof, while a follower and set-screw is employed to compress the curved face of the block 80 against the thill-eye; but I expressly disclaim both of said constructions.

85 What I do claim, however, is—

The combination, with the cast-metal case or box E, having posterior cavity, E², and concave face E', of the block F, plate G, and set-screw H, when arranged and constructed as described, for the purposes specified.

SAMUEL J. BINGHAM.
